UNITED STATES PATENT OFFICE.

RICHARD C. KEOGAN, OF SOUTH BEND, INDIANA.

TRAFFIC SIGNAL.

Application filed September 27, 1926. Serial No. 138,093.

The invention relates to traffic signals and has for its object to provide a device of this character particularly adapted for use in block systems, and provided with sight openings across which a beam of light passes and assumes different positions in the sight openings, thereby allowing an operator of a vehicle to easily estimate when approaching the crossing about how long the light has been 10 on, and how long before the change, thereby obviating the present practice of operators of vehicles speeding to pass the light, without any idea of the period of illumination.

A further object is to supply light for 15 the sight openings from a single lamp around which lamp a drum rotates and is provided with lenses through which the light rays project, thereby obviating expensive mechanism at present used where a number 20 of lamps are used.

A further object is to provide the drum with a downwardly extending tubular member through which the light conduit extends and which tubular member terminates 25 in a base anti-frictionally supported in the bottom of the casing.

A further object is to provide the upper 30 end of the tubular member with a spider connected to the under side of the rotatable drum, and through which spider light rays from the single lamp project downwardly for illuminating the chamber of the casing and the lower portions of the sight openings on which indicia may be placed.

A further object is to provide outwardly 35 extending vanes at opposite sides of the sight openings for partially cutting off the view from positions at a right angle to the vertical planes of the sight openings.

With the above and other objects in view 40 the invention resides in the combination and arrangement of parts as hereinafter set forth, shown in the drawing, described and claimed, it being understood that changes in 45 the precise embodiment of the invention may be made within the scope of what is claimed without departing from the spirit of the invention.

Figure 1 is a front elevation of the signal 50 light.

Figure 2 is a vertical longitudinal sectional view through the signal device, the upper portion shown in elevation.

Figure 3 is a horizontal sectional view 55 through the signalling device taken on line 3-3 of Figure 2.

Figure 4 is a horizontal sectional view through the tubular member, showing the driving means therefor.

Referring to the drawing, the numeral 1 designates the main stationary casing of the signalling device, which casing at the opposite four sides thereof is provided with oblong shaped sight openings 2, in which are disposed transparent closures 3, and the 60 lower portions of said transparent members 3 may be provided with indicia 4 of any desired subject matter. Extending outwardly from the ends of the transparent members 3 are vanes 5, which are vertically disposed 65 and cut off side light rays to a certain extent, and extending around the casing above the upper wide ends of the vanes 5 is a water shed 6, as well as means for cutting off upwardly directed rays. 70

In block signal systems as at present constructed, a number of lamps are used and a complicated switch mechanism. In the present device a single lamp 7 is provided, which lamp is supported on the upper end of 80 the conduit 8, which extends upwardly through the bottom of the casing 1, as clearly shown in Figure 2. Rotatably mounted within the casing 1 is a drum 8' in the chamber 9 of which the lamp 7 is disposed, and 85 which drum preferably registers with the upper portions of the transparent members 3, whereby light rays projected from the lamp 7 will pass through the oppositely disposed red and green lenses 10 and 11, and 90 thence through the transparent members 3, as the drum is rotated. It will be noted that the lenses 11 are relatively small in relation to the transparent members 3, consequently 95 as the drum 8' rotates, areas of light rays will pass horizontally across the transparent members 3. For instance, referring to Figure 1, the lens 10, when it reaches the dotted line position *a* is just coming on, and when it reaches the dotted line position *b*, the operator of an approaching vehicle will know 100 not only is the danger signal on, but that it has reached one half of its period and where it is a ten second light it will be five seconds before it reaches the position *c*, which is the 105 change position, therefore during the visibility of the red and green signals, an approaching operator can easily estimate the length of time a block or go signal has been on, and the amount of time which will elapse 110 before the change, thereby obviating the dangerous practice of motorists trying to

race to make a crossing before the change. It will be noted that when the lenses register with the corners 12, there is a period when the lenses are concealed and light rays cut off, and at which period pedestrians may cross the street.

Surrounding the conduit 8 and rotatably mounted around the same is a vertically disposed sleeve 13, the upper end of which is provided with a spider 14 which is secured at 15 to the under side of the drum, and through the openings 14a in said spider light rays from the lamp 7 will pass downwardly into the lower portion of the chamber of the casing 1 below the drum 8' where the indicia 4 will be illuminated, and which illumination will be constant. The lower end of the tubular member 13 is provided with a base 16, which is mounted on anti frictional bearings 17, thereby insuring a smooth steady rotation and elimination of friction. Tubular member 13 is provided with gear teeth 18 extending entirely around the same, and with which gear teeth a slow worm 19 engages, and which worm may vary according to the periods of illumination through the lenses 10 and 11. Worm 19 is carried by a shaft 20, which shaft is driven by a motor 21, therefore it will be seen that complicated mechanisms are eliminated.

From the above it will be seen that a traffic signal is provided which is simple in construction, complicated operating and switch mechanism eliminated, a single lamp used for illuminating purposes, and one wherein the operator of an approaching vehicle can easily ascertain from the position of the light on the transparent members 3 how long the light has been on and the period of time before the same will be obscured.

The invention having been set forth what is claimed as new and useful is:—

1. A traffic signal comprising a casing

having sight openings in the sides thereof, a lamp within the casing, a rotatable drum 45 within the casing, said light being disposed within said drum, said drum having light passages of relatively small area in relation to the sight openings in the casing and positioned whereby during the rotation of the 50 drum light rays projected through the light passages of the drum will pass through the sight openings and will move horizontally across said sight openings.

2. A traffic signal comprising a stationary 55 casing having sight openings in opposite sides thereof, a rotatable drum within the casing and having light ray openings in opposite sides thereof, a lamp in said drum, a bottom carried by said drum, a rotatable 60 supporting bracket for said drum, means whereby light rays from the lamp will pass downwardly through the drum into the chamber of the casing below the drum, whereby indicia within the sight openings 65 below the drum will be illuminated, and driving means for said supporting bracket.

3. A traffic signal comprising a casing, a lamp within said casing, said casing having sight openings in its opposite sides, a rotatable drum within the casing, light ray lenses carried by opposite sides of the drum, a vertically disposed supporting member for the lamp, a supporting sleeve carried by the drum and rotatably mounted around the 75 lamp supporting member, a supporting bearing for the lower end of the sleeve, an annular member having light passages carried by the upper end of the sleeve and connected to the drum in registration with an opening in the drum and through which passages light rays pass downwardly from the lamp into the casing below the drum.

In testimony whereof I affix my signature.

RICHARD C. KEOGAN.
